both of Calif.

Primary Examiner—James R. Largen
Attorney, Agent, or Firm—Richard L. Gausewitz

[73] Assignee: **South Pacific Industries, Inc.**, Santa
Ana, Calif.

[57] CLAIM

[**] Term: **14 Years**

The design for an aerator for swimming pools or the
like, substantially as shown and described.

[21] Appl. No.: **806,582**

DESCRIPTION

[22] Filed: **Jun. 15, 1977**

FIG. 1 is a perspective view taken from the top, front
and one side of an aerator for swimming pools or the
like showing our new design;

[51] Int. Cl. .... **D15—02**

FIG. 2 is an elevational view taken from the side oppo-
site that shown in FIG. 1;

[52] U.S. Cl. **D15/7**

FIG. 3 is a rear elevational view thereof;

[58] Field of Search **D15/7, 8-9;**

FIG. 4 is a top plan view thereof;

D23/139-167; 4/172.15, 172.17, 178-180

FIG. 5 is a bottom plan view thereof; and
FIG. 6 is a perspective view taken from the top, front
and one side of a modified form of the aerator for swim-
ming pools or the like shown in FIG. 1, wherein said
modification resides in the elongated aerator housing.
